INTERLOCKED DOUBLE WALL

George Stavrou, Brooklyn, N. Y.

Application December 14, 1949, Serial No. 132,975

8 Claims. (Cl. 72—38)

1

This invention relates to an interlocked double wall and more particularly to a novel type of interlockable brick unit for use in the construction of building walls.

Heretofore, brick building walls have been laid one above the other with mortar or cement between them. They have been reinforced by means of wood and/or iron beams. Furthermore, such walls, while being able to withstand considerable stress and strain, are relatively expensive since they require crossbeam supports and relatively highly skilled workmen.

With the above disadvantages in view, it is an object of my invention to provide, as a fundamental building unit, a brick of such simplicity that relatively little skill in brick laying is required.

It is another object of my invention to provide a brick of such outline that it can be readily interlocked with other bricks of similar construction so that it will form a completed wall for buildings of any suitable size.

Still another object of my invention is to provide an interlocking brick unit adapted to provide a plurality of spaced walls with intermediate spaces in which means for the passage or installation therein of piping or conduits can be laid and which spaces may be filled with any suitable filler or material such as concrete or insulation material.

A more specific object of my invention is to provide a brick unit having vertically extending means with intermediate spaces between the means for interlocking with similar units, said means being provided with male projections and notches adapted to engage the notches and projections, respectively, of adjacent brick units.

Another specific object of my invention is to provide a combination of interlockable brick units forming intermediate spaces for the installation therein of piping for any suitable purpose.

Other objects and advantageous features of my invention will become apparent from the following detailed description taken in connection with the attached drawings wherein:

Fig. 1 is a preferred embodiment of my invention showing a perspective view of a brick unit;

Fig. 2 is a perspective view of another form of the unit shown in Fig. 1;

Fig. 3 is a perspective view of a modification of the embodiments shown in Figs. 1 and 2 and is used in connection with said embodiments to join with the ends thereof at right angles;

Fig. 4 is a perspective view of a brick unit used for joining the opposed ends of the embodiments shown in Figs. 1 and 2;

2

Fig. 5 is a top plan view showing the combination of the units illustrated in Figs. 1 to 4, inclusive;

Fig. 6 is a side view of Fig. 5; and

Figure 7 is a top plan view similar to Figure 5 showing the combination of the brick units provided with a suitable filler material.

Referring now more particularly to the drawings in which similar reference numerals refer to like parts throughout, it will be noted that I provide a building brick 10 containing a long body portion 11. Said long portion contains a number of intermediate, vertical, upper and lower extensions 12 and 13, respectively, whose side walls 14 and 15, respectively, are provided with a notch or semi-cylindrical recess 16 which is adapted to retain therein cement, mortar, or other binding material when said brick 10 is laid. It will be noted that said notches 16 are disposed in the center of the walls 14 and 15. There are also provided at the end of said brick 10 terminal sections 17 whose respective inner, upper and lower faces 18 and 19 are provided with a notch 20 while the front and rear walls 21 and 22, respectively, of said terminal sections are also provided with vertical notches or recesses 23 and 24, respectively. Intermediate the extensions or sections 12 and 13, as shown, it will be noted that there is provided an upper and lower intermediate space 25 and 26, respectively, for accommodating an adjacent brick unit of similar construction in the corresponding intermediate spaces 25 and 26 thereof, as shown in Figures 5 to 7 of the drawing.

The unit 10 as shown in Fig. 1 is intended for the corner portion of one or more vertical walls, while the unit 10a shown in Fig. 2 is of the same construction but is much shorter than that shown in Fig. 1 and is intended for the front portion of the wall to be built with such units, although either unit, because of the similarity of construction, may be used interchangeably and at right angles relatively of each other.

In Fig. 3, I show a joining brick unit 27 which is substantially of H-shape and consists of two vertical sections 28 and 29, respectively, and an intermediate, interconnecting, horizontal section 30. The upwardly extending sections 28 and 29, respectively, are each provided at their opposed faces 31 and 32, respectively, with a vertical notch, recess or groove 33, while the front, side and rear faces 34, 35 and 36 respectively, of the sections 28 and 29, respectively, are provided with vertical or male projections 37 which are adapted to engage the notches or recesses 23 of the terminal portions 17 of the units shown in Figs. 1 and 2, respectively.

In Fig. 4, I show a brick unit 38 in which the outer face 39 is straight while the two side faces 40 and 41, respectively, are each provided with a projection 37 so as to join with the notches 23 of the terminal portion 17 of the unit 10 and 10a shown in Figs. 1 and 2, respectively. The inner face 42 of said unit as shown in Figs. 4, 5 and 7 has a recess 43 so as to accommodate a suitable filling material 44 when a plurality of walls are constructed such as shown in Figs. 5 to 7, inclusive.

It will be noted that blocks 10 or 10a, respectively, as shown in either Figure 1 or 2, can be superimposed above each other crosswise, whereby the intermediate spaces 25 and 26 of one block are adapted to accommodate the portions between extensions 12 and 13 of a similar type of block so as to be bounded between the terminal and extending portions of each block.

It will also be noted from the foregoing description taken in conjunction with the accompanying drawings that a block of the type made according to my invention can be readily superimposed above blocks of similar construction whereby one or more walls can be built within a relatively short time, it being understood that the blocks when superimposed are at right angles to each other. The spaces 25 and 26 between any protruding terminal portions as shown in Figs. 1 and 2, are filled in by means of interconnecting block 27 or covered by blocks 38 as shown in Figs. 5, 6 and 7. The terminal portions 17 can be readily joined at right angles with interconnecting block 27 or 38 whereby the projections 37 of either block will fit into any of the notches 23 or 24 of said terminal portions. Furthermore, for example, block 27 may be fitted between portion 17 and upward or downward extension 12 or 13 to obtain a desired fit. In such case the portion 30 of block 27 fits in the intermediate space 25 or 26. In the alternative the portions 28 or 29 may fit between such portions above indicated. By a combination of such blocks units it is relatively easy to lay piping or conduits 45 in a vertical or horizontal manner in these walls as shown in Figs. 5 to 7. Furthermore, the intermediate spaces formed between the walls built by these blocks can be readily filled in with any suitable material 44 depending upon the purpose for which such material is used such as cement, mortar, or sand as a filler, or insulating material for insulation purposes.

Blocks made according to my invention are highly useful for any type of construction work such as for foundations, for building inside and outside walls, for window or door frames. These blocks are made of the usual type of construction material and are easily interlockable, are provided with notches intermediate the terminal portions of the block for retaining binding material therein while the terminal portion of the building blocks are provided with front, side and rear walled recesses or notches which are adapted to accommodate the projections of the interconnecting blocks such as shown in Figs. 3 and 4.

Having described illustrative embodiments of the invention, it is pointed out that various changes and modifications therein may be made without departing from the scope of the invention as set forth in the following claims.

I claim:

1. A double wall structure comprising a plurality of spaced longitudinal walls including substantially rectangular longitudinal body members having recesses longitudinally equi-spaced in the

top and bottom thereof and opposite one another, said body members being placed on top of each other with recesses of adjacent members aligned thereby forming openings, a plurality of cross-members extending transversely between and interlocking said walls and having recesses equi-spaced therealong in the top and bottom thereof and opposite one another, said recesses being spaced from the ends of said cross-members, the end portions of said cross-members projecting through said openings beyond at least one of said walls with recesses of said cross-members interlocking with said openings, and a plurality of interconnecting face members positioned in alignment with one another and between longitudinally adjacent end portions and interlocked therewith, said end portions and said face members forming a substantially plane face.

2. A double wall structure according to claim 1 wherein said interconnecting face members are provided with recesses on the side facing the inner side thereof.

3. A double wall structure according to claim 2 wherein said longitudinal body members are provided with semi-cylindrical grooves in the faces thereof which constitute opposite faces of said recesses, said grooves running substantially in the direction of said recesses.

4. The double wall structure according to claim 3 wherein said cross-members are provided with semi-cylindrical grooves in the faces thereof which constitute opposite faces of said recesses.

5. The double wall structure according to claim 1 wherein the depth of each recess is approximately one-quarter of the dimension of their respective member in the direction of the recesses.

6. A double wall structure comprising at least a pair of spaced longitudinal walls including substantially rectangular longitudinal body members having projections longitudinally equi-spaced upwardly and downwardly and opposite one another, said body members being placed on top of each other with projections of adjacent members aligned with one another thereby forming openings therebetween, at least two cross-members extending transversely between and interlocking said walls and having projections equi-spaced upwardly and downwardly therealong thereby forming recesses between said projections, said projections being opposite one another and forming the end portions of said cross-members, said end portions projecting through said openings beyond at least one of said longitudinal walls with recesses of said cross-members interlocking with said openings, and a plurality of inter-connecting face members positioned in alignment with one another and between longitudinally extending end portions and interlocked therewith, said end portions and said face members forming a substantially plane wall.

7. The double wall structure according to claim 6 wherein said inter-connecting face members are provided with recesses on the side facing the inner side thereof.

8. The double wall structure according to claim 7 wherein said interconnecting face members are provided with lateral projections interlocking with corresponding grooves provided in the side faces of the end portions of said cross members.
